DESIGN.

F. MANKEY.

OPEN WORK PANEL.

No. 16,427.

Patented Dec. 29, 1885.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 16,427, dated December 29, 1885.

Application filed November 13, 1885. Serial No. 182,763. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

Extending through the panel are octagonal openings, each having four straight sides, A B C D, and four inwardly-convex sides, E F G H. The straight sides alternate with the convex sides. The said openings are disposed at regular intervals in rows, the openings 15 in one row alternating with the openings in the succeeding row. Upon the face of the panel, and extending in a diagonal direction across the same, are scores or channels I and oppositely-inclined channels J. At the points 20 of intersection of these channels may appear circular depressions K.

I claim—

1. The design for an open-work panel, substantially as herein shown and described, which consists in the octagonal openings A B C D E 25 F G H, arranged in rows and alternating in adjacent rows and on the face of the panel, the inclined channels I, and oppositely-inclined channels J.

2. The design for an open-work panel, substantially as herein shown and described, which consists in the octagonal openings A B C D E F G H, arranged in rows and alternating in adjacent rows, and on the face of the panel the inclined channels I, oppositely-inclined 35 channels J, and circular depressions K.

FREDERICK MANKEY.
